UNITED STATES PATENT OFFICE

157,480

GRILL

Samuel D. Foss, Bay City, Mich., assignor to Nichols-Foss Packing Co., Bay City, Mich.

Application November 12, 1948, Serial No. 149,577

Term of patent 14 years

(Cl. D44—1)

To all whom it may concern:

Be it known that I, Samuel D. Foss, a citizen of the United States of America, and a resident of Bay City, in the county of Bay and State of Michigan, have invented a new, original, and ornamental Design for a Grill, of which the following is a specification, reference being had to the accompanying drawing, forming part thereof.

In the drawing:

Fig. 1 is a perspective view of a grill, showing my new design.

Fig. 2 is an edge-elevational view thereof.

I claim:

The ornamental design for a grill, as shown.

SAMUEL D. FOSS.
